Specification for Design.

Patented Oct. 14, 1919.

Application filed June 16, 1917. Serial No. 175,217. Term of patent 14 years.

To all whom it may concern:

Be it known that I, ALBERT E. HOLADAY, a citizen of the United States, residing at Naugatuck, in the county of New Haven and State of Connecticut, have invented a new, original, and ornamental Design for Pressure-Screws for Clothes-Wringers, of which the following is a specification, reference being had to the accompanying drawing, forming part thereof.

Figure 1 is a perspective view of a pressure screw showing my design.

Copies of this patent may be obtained for five cents each, by addressing the "Commissioner of Patents, Washington, D. C."

Fig. 2 is a plan view; and
Fig. 3 is a sectional view.

I claim:

The ornamental design for a pressure screw for clothes wringers, as shown.

ALBERT E. HOLADAY.
